INVENTOR

Frederick Mesinger

BY C. P. Gofel
his ATTORNEY

UNITED STATES PATENT OFFICE.

FREDERICK MESINGER, OF NEW YORK, N. Y.

SADDLE.

Application filed September 7, 1922. Serial No. 586,577.

To all whom it may concern:

Be it known that I, FREDERICK MESINGER, a citizen of the United States, and a resident of the city, county, and State of New York, **5** have invented a certain new and useful Improvement in Saddles, of which the following is a specification.

This invention relates to saddles and more particularly to saddles of that character designed for use upon motorcycles and similar vehicles.

It is the primary object and purpose of my present invention to provide such a saddle with a detachable back rest or support. **15** The saddle provided with the back rest in addition to affording a more comfortable seat for the driver, may also be used in place of the ordinary side car with which some motorcycles are equipped.

20 It is a further object of the invention to provide a detachable back rest for motorcycle saddles which greatly adds to the physical comfort of the rider but which at the same time will not materially increase **25** the manufacturing cost of such saddles or the selling price of motorcycles or other vehicles equipped therewith.

With the above and other objects in view, the invention consists in the improved vehicle saddle and in the form, construction and relative arrangement of the several parts as will be hereinafter more fully described, illustrated in the accompanying drawing and subsequently incorporated in the subjoined claims.

In the drawing wherein I have illustrated one practical and desirable embodiment of the invention and in which similar reference characters designate corresponding parts **40** throughout the several views:

Figure 1 is a plan view of a motorcycle saddle having the back rest or support applied thereto, and

Figure 2 is a sectional view taken on the **45** line 2-2 of Figure 1.

In the drawing I have illustrated the saddle proper of a general form or shape which is quite familiar in the motorcycle art. It is to be understood, however, that such form **50** or shape of the saddle is not an essential feature of my present improvements and that the latter may be applied and advantageously used in connection with various other sizes or shapes of the saddle. As here-
55 in shown, the saddle proper is provided with a properly stamped or shaped base or stiff-

ening plate 5 upon the upper side of which the usual padding material 6 is arranged covered by the leather 7. The edges of this leather 7 extend beyond the edges of the **60** plate and are stitched or otherwise permanently secured to a selvedge strip of leather 8 which is riveted as at 9 to the lower face of the plate 5 and also projects beyond the edge of said plate. **65**

The rear portion of the stiffening plate 5 is upwardly curved and is provided with a plurality of spaced integrally formed internally threaded bosses 10 adjacent to its upper edge which project into the space occupied by the padding material 6. It will be understood that the selvedge strip 8 has openings therein coinciding with the threaded bores of the bosses 10. As these bosses are completely concealed and therefore invisible, the saddle proper has the same outward appearance as the ordinary saddle of this type. **70**

The back rest with which the saddle may be provided at the option of the rider, consists of a rigid body plate 11. The rear side of this plate is entirely covered by a sheet of leather 12 which projects beyond the edges of the plate and is stitched or otherwise permanently secured to the edges of the **80** front leather 13 between which and the plate 11 the padding material 14 is placed. The padded area of the back rest is less than the surface area of the plate 11 as the lower portion of the front leather sheet 13 is closely engaged with the front face of said plate over the lower marginal section thereof, as indicated at 15. This lower portion of plate **85** 11 and the rear and front leather sheets 12 and 13 are provided at spaced points with openings to receive the attaching bolts 16. These bolts are adapted to be threaded into the bosses 10 so as to tightly clamp the lower margin of the back rest against the rear side of the saddle seat. Thus as seen in Figure **90** 2 of the drawing, the back rest is very rigidly supported upon the upper rear portion of the saddle proper. The back rest preferably extends across substantially the entire width of the saddle and thus provides an extensive padded area affording a comfortable rest or support for the rider's back. When it is not desired to use the back rest it can be easily and quickly detached from the saddle seat by simply removing the bolt 16. **95**

From the foregoing description considered in connection with the accompanying draw-

ing, the construction, manner of use and the several advantages of my present invention will be fully and clearly understood. It will be appreciated that the back rest or support 5 as a supplement to saddles such as are used upon motorcycles, will greatly add to the physical comfort of the rider. At the same time the back rest and the attaching means therefor is of such simple construction that 10 it can be produced at low cost and will not therefore materially add to the selling price of such vehicles. It will be seen that when applied and rigidly secured in position, the back rest constitutes in effect a continuation 15 of the saddle seat, there being no appreciable intervening space between the seat and the back rest. Thus the saddle with the back rest applied will present a neat and attractive appearance.

20 I have herein shown and described one construction of the detachable back rest and an attaching means therefor which I have found to be very satisfactory in actual use. Nevertheless it is apparent that the device 25 is susceptible of embodiment in other alternative forms and I accordingly reserve the privilege of adopting all such legitimate changes in the form, construction and relative arrangement of the several parts as may 30 be fairly embodied within the spirit and scope of the invention as claimed.

I claim:

1. In combination with a vehicle saddle seat having a body plate upholstered on one 35 side and upwardly curved at its rear end, a back rest for said seat also having a body plate upholstered on one side and the upholstery thereof along one of its marginal edges corresponding in contour to the upper 40 rear edge of the body plate of said seat, and means for detachably and rigidly securing said back rest to the body plate of the seat with said marginal edge of the up-

holstery thereof in close proximity to the rear upper end of the upholstery of the saddle seat, whereby the back rest when applied, constitutes in effect a continuous part of the seat structure. 45

2. In combination with the vehicle saddle seat, a back rest therefor adapted to be arranged at the rear edge of the seat and constructed to constitute in effect a continuation of the saddle seat, the saddle seat including a body plate having spaced internally threaded bosses thereon and said back rest 50 also having a rigid body plate provided with bolt receiving openings, and attaching bolts adapted to be engaged through said openings and threaded in said bosses to detachably secure the back rest rigidly to the body 55 of the saddle seat. 60

3. In combination with a vehicle saddle seat having a base plate provided adjacent its upper rear edge with internally threaded bosses, a supplementary back rest or support for said seat including a rigid body plate having padding on the front side thereof and a leather covering sheet for said padding contacting closely with the surface of said plate along one marginal area thereof, a leather sheet covering the rear surface of said plate and secured to the front leather sheet beyond the edges of the plate, said marginal area of the plate and leather 65 sheets having spaced openings therein, and 70 attaching bolts adapted to be engaged through said openings and threaded into the bosses on the body plate of the saddle seat to detachably and rigidly secure the back 75 rest in position whereby the latter in effect constitutes a continuation of the saddle seat. 80

In testimony that I claim the foregoing as my invention, I have signed my name hereunder.

FREDERICK MESINGER.
